UNITED STATES PATENT OFFICE.

PETER J. SWARTWOOD, OF MOUNTAINTOP, PENNSYLVANIA.

GAME APPARATUS.

1,221,244.

Specification of Letters Patent.

Patented Apr. 3, 1917.

Application filed February 13, 1915. Serial No. 7,989.

To all whom it may concern:

Be it known that I, PETER J. SWARTWOOD, a citizen of the United States, residing at Mountaintop, in the county of Luzerne and State of Pennsylvania, have invented certain new and useful Improvements in Game Apparatus; and I do hereby declare the following to be a full, clear, and exact description of the invention, such as will enable others skilled in the art to which it appertains to make and use the same.

This invention relates to game apparatus and one of the principal objects of the invention is to provide a game of chance which simulates a war between two or four opponents, the object of the game being to enter the men in a fort disposed centrally upon the game board.

The foregoing and other objects may be attained by means of the construction illustrated in the accompanying drawings, in which—

Figure 1 is a top plan view of a game board made in accordance with this invention,

Fig. 2 is a top plan view of a dial having a spinning hand pivoted thereto for indicating the movements of the men on the board,

Fig. 3 is a view in elevation of one of the men or accessories to the game,

Fig. 4 is a similar view of one of the opposing men.

Referring to the drawings, and more particularly to Fig. 1, the numeral 1 designates a game board of any suitable size made in two sections connected together by hinges 2 and adapted to be folded similar to the ordinary checker board. The board when opened out is substantially square, and represented on the board at each of its four sides near the outer edges, and at the left of the center of the board are tents 3. Starting from the front opening of each of the tents is a line of marks consisting of four squares in width, the first four of which are numbered 1, 2, 3 and 4, as indicated at 4, and a series of squares extend from this point across the board and are formed by longitudinal lines 5 and transverse lines 6. At certain points in the lines of march are obstacles 7 which may be represented in a contrasting color, and at points where the roads or lines of march intersect

are rectangular fields 8 of contrasting color. 55 Each of the lines of march are provided with a curve 9, and the representation of a lake at the center of the curve. The line of march from the lake 10 to the central fort 11 is substantially parallel to the line of 60 march leading from the tent across the board.

As shown, there are four lines of march leading one from each tent to the fort, and these lines of march are differently colored, 65 so that each player may have game pieces corresponding to the color of the lines of march.

Referring to Fig. 3 of the drawings, one of the game pieces is shown as a soldier 70 mounted upon a base 7 and these bases may be rectangular in form, similar to the size and shape of the squares on the board and may be colored to correspond with each of the lines of march. Each player has four 75 soldiers and they are placed on the spots 1, 2, 3 and 4 to start the game.

Fig. 4 illustrates a game piece 7 representing a soldier of a somewhat different type from the other and provided with a 80 base 8 which is correspondingly colored, and the men for each line of march may be different in form as well as color.

Referring to Fig. 2, the numeral 12 designates a dial or disk having a hand or pointer 85 13 pivoted on a pin centrally, as at 14, through the disk, and provided with a finger hold 15 at one end and a point 16 at the opposite end. Between the periphery of the disk and a circular line 17 drawn 90 in a circle inside the periphery are numerals 18 disposed at diametrically opposite sides of the disk, and shown as the ordinals 5. At midway points between the ordinals 5 are the ordinals 8 as shown at 19. Represented within an inner circle is an annular series of legends 20 which consists of the words "No. 1"—1, "No. 2"—2, "No. 3"—3, "No. 4"—4, and "No. 1"—2, "No. 2"—3, "No. 3"—1, etc. 100

To play the game the men are placed on the spots 1, 2, 3 and 4 and the first player spins the hand 13, and should the hand stop at "No. 4"—2, the man on the spot 4 is moved forward two squares. The next 105 player spins the hand 13 and he moves the game man according to the number that the hand 13 registers from his station or start-

point. This is continued until the fourth player has spun the hand 13 and moved the game man accordingly.

The first player again spins the hand 13 and if the hand stops at a point indicating number 4 with some other number in connection therewith the same game man that was previously moved is again moved according to the second number appearing below the line on the dial. If another number is registered the game man that is positioned in the space of the starting point which corresponds with this number appearing above the line of the dial is moved accordingly. If the game man when being moved happens to land upon the colored position on spaces 7 a penalty of two spaces is inflicted on the game man and he is compelled to return the two spaces. When the game man has reached a field 8 a number must be spun which will correspond with the moves occurring between the game man and the field before said game man can enter. After the game man has been entered to the field 8 it is necessary that the players spin the hand 13 to register 8 as illustrated at 19 of Fig. 2, and then the game man may continue onward. For a game man to pass the lake 10 it is necessary that the players spin the hand 13 to register 5 as illustrated at 18 of Fig. 2. To enter the fort 11 which is the goal of the game it is necessary that an exact number be spun to correspond with the game man and with the spaces occurring between said

game man and the fort 11. When the hand stops on 5 and 8, certain obstacles in the lines of march are overcome.

The player who first gets his men inside the fort 11 wins the game, and if partners are playing both partners must get his men within the fort in order to win. There are many ways of playing the game, and the foregoing description is deemed sufficient.

Various changes may be made in the details of construction without departing from the spirit and scope of the invention as defined in the claim.

What is claimed is:—

A game board of rectangular formation, 50 pairs of tents arranged adjacent each corner of the board, a pair of S-shaped lines of march located on the board and arranged to intercross each other and having their ends terminating adjacent the tents, a fort located at a point central of the ends of each of the S-shaped lines of march, rectangular fields of contrasting colors located at points of intercrossing of the S-shaped lines of march, and each S-shaped line of march 55 being divided into four lines of march to receive game pieces comprising soldiers, and a chance controlled device to indicate the movement of the soldiers.

In testimony whereof I affix my signature 60 in presence of two witnesses.

PETER J. SWARTWOOD.
